VALVE CONTROL MECHANISM FOR
RECIPROCATED DEVICES

Forrest R. Whitcomb, Worcester, Mass.

Application February 26, 1947, Serial No. 731,146

4 Claims. (Cl. 121—45)

1

This invention relates to machines in which a hydraulically operated device is automatically reciprocated between normal limits and in which extended travel or over-run is at times desired, as for work inspection or reloading.

The invention is particularly applicable to automatic cutlery-honing machines but is also capable of more general use.

It is the general object of this invention to provide improved mechanism by which the range of reciprocation of the hydraulically operated device may be conveniently changed from short or normal travel to long travel or over-run, as and when required.

A further object is to provide a construction in which complete stopping of reciprocation for work inspection or reloading may be conveniently associated with over-run of the reciprocated device.

Another object is to provide valve control mechanism which will be automatically reset for short or normal travel when the machine is again started in operation after over-run.

My invention further relates to arrangements and combinations of parts which will be herein-after described and more particularly pointed out in the appended claims.

A preferred form of the invention is shown in the drawings, in which

Fig. 1 is a plan view of my improved valve control mechanism;

Fig. 2 is an enlarged plan view of certain parts shown in Fig. 1;

Fig. 3 is a side elevation, looking in the direction of the arrow 3 in Fig. 1;

Fig. 4 is a rear view, looking in the direction of the arrow 4 in Fig. 3;

Fig. 5 is a detail sectional rear elevation, taken along the line 5—5 in Fig. 2;

Fig. 6 is an enlarged plan view, partly in section, of a loading or lost-motion connection shown in Fig. 1;

Fig. 7 is a detail plan view of a double reversing finger, looking in the direction of the arrow 7 in Fig. 4; and

Fig. 8 is a rear view of a latch plate to be described, the view being a part section on the line 8—8 in Fig. 2.

Referring to the drawings, I have shown portions of a machine comprising a fixed column 10 (Fig. 3) on which a sleeve 11 is slidably mounted. A work-supporting head may be associated with the sleeve 11 and is guided on the column 10 for vertical reciprocation. Upright rods 12 and 14 are associated with the work head and share the vertical reciprocation thereof.

The reciprocated parts are actuated by any suitable hydraulic mechanism, controlled by a throttle valve 15 (Fig. 4) having an arm 16 connected by a link 17 to a lever 18 (Fig. 3) pivoted at

19 on a fixed bracket 20. When the link 17 is shifted to the right in Fig. 4, the throttle valve 15 is closed to stop the reciprocating travel of the work head and associated parts.

5 The bracket 20 is carried by a support 22 firmly clamped to the fixed column 10. A reversing valve 23 (Fig. 4) is provided between the throttle valve 15 and the hydraulic reciprocating mechanism and is connected by pipes 24 to a pilot or control valve 30 (Fig. 1). The control valve 30 has an actuating shaft 31 provided with a stop plate 32 (Fig. 5) secured thereto and having lugs 33 and 34 adapted to engage a stop pin 35.

15 When the lug 33 engages the stop pin 35, liquid will flow through certain of the pipes 24 to set the reversing valve 23 for travel of the reciprocating parts in one direction, and when the valve 30 is shifted to engage the lug 34 with the stop pin 35, the reversing valve will be positioned to cause travel of the reciprocating parts in the opposite direction.

20 A spring 36 (Fig. 5) is mounted on a rod 37 which is slidable in a pivot block 38 and which is pivotally connected by a stud 39 to the stop plate 32. The centers of the shaft 31, block 38 and stud 39 are so related that the spring 36 passes dead center as the stop plate is shifted and yieldingly holds the plate in either of its extreme positions.

25 The shaft 31 is positioned by actuating members 40, 41 and 42 (Fig. 4) which may be clamped in vertically adjusted positions on the reciprocating rod 12. The actuating member 40 has two actuating fingers 43 and 44 (Fig. 7) and the members 41 and 42 have single actuating fingers 45 and 46. These actuating fingers engage arms 30 50 and 51 (Fig. 2) on a sleeve 52 keyed to the outer end portion of the shaft 31 and freely slidably thereon. A washer 54 on the end of the shaft 31 limits the outward travel of the sleeve 52.

35 The fingers 44 and 45 engage the arms 50 and 51 respectively when the sleeve 52 is in its normal or outer position as shown in Fig. 1, and the fingers 43 and 46 engage the arms 50 and 51 when the sleeve 52 is shifted to the inner or run-off position shown in Fig. 2.

40 The axial shifting of the sleeve 52 (Fig. 2) on the shaft 31 is controlled by a yoke lever 60 mounted on an upright rod 61 (Figs. 3 and 4) pivoted in fixed bearings 62 and 63. The yoke arms 65 are provided with rolls 66 positioned in a groove or annular recess 67 in a collar 68 secured to the sliding sleeve 52 previously described.

45 A latch plate 70 (Fig. 2) is secured to the collar 68 for axial sliding movement therewith, and has a segmental portion 71 (Fig. 8) of increased radius which is beveled for engagement in certain angular positions by a latch 72 mounted on a fixed pivot 73.

50 At its lower end, the sleeve-shifting rod 61 has

an arm 75 (Fig. 2) to which the head 76 of an actuating rod 77 is pivotally connected. At its left-hand end (as viewed in Figs. 1 and 3) the rod 77 passes freely through a block 78 which is pivoted at 79 (Fig. 1) in the outer end of a lever 80. The lever 80 has a floating pivotal connection at 81 to a plate 82 pivoted at 19 and formed integral with the throttle valve actuating lever 18 (Fig. 3) previously described. The plate 82 has depending pins 84 and 85 which limit the swinging movement of the lever 80 relative to the plate 82.

A collar 88 (Fig. 3) on the rod 77 limits movement of the rod 77 relative to the block 78 to the left in Fig. 3, and a spring 86 mounted on the rod 77 engages lock nuts 87 on the rod and yieldingly holds the block 78 against the collar 88 but permits movement of the block to the left in Fig. 3 without corresponding movement of the rod 77.

At its inner end, the lever 80 has a swivel connection 89 (Figs. 1 and 6) to a bar 90 which is slidably connected with a second bar 91 which extends to the front of the machine, where it is connected to a handle 92 which is mounted on a fixed pivot 93.

A sliding connection between the bars 90 and 91 is shown in detail in Fig. 6. The bar 91 is slotted at 94 to receive studs 95 fixed in the bar 90. A spring 96 connects a stud 97 in the bar 91 to a stud 98 in the bar 90 and normally holds the bars 90 and 91 in the relative positions shown in Fig. 6.

The bar 90 has a notch 100 (Fig. 6) in its upper edge, which notch is adapted to receive the out-turned end 101 of a latch lever 102 (Fig. 1) which is mounted on a fixed stud 103 and which has its rear end portion positioned for engagement by a collar 104 (Figs. 1 and 3) mounted on the lower end of the vertically reciprocated rod 14.

The collar 104 engages the latch lever 102 as the collar 104 approaches its lower limit of travel, so that the latch lever becomes inoperative at such lower limit but is otherwise operative to hold the lever 80 and associated parts in the running position shown in Fig. 1.

A spring-pressed ball 106 (Fig. 1) coacts with recesses 107 and 108 in the bar 91 to hold the bar yieldingly in either mid or forward positions.

Having described the details of construction of my improved valve control mechanism, I will now describe the operation thereof in controlling the limits of travel and the stopping and starting of the vertically reciprocated parts.

Operation

The parts are shown in Fig. 1 in position for automatic reciprocation of the work head and associated parts with short or normal travel. The bar 90 is held in its rearmost or right-hand position by the latch lever 102. The lever 80 has moved the arms 65 of the yoke lever 60 to the position shown, with the sleeve 52 and associated valve operating arms 50 and 51 in vertical alignment with the upper finger 44 and the middle finger 45 (Fig. 4).

At the same time, the lever 80 has engaged the pin 84 and has moved the plate 82 and lever 18 (Fig. 3) clockwise to draw the link 17 to the left in Fig. 4 and thus open the main throttle valve 15 so that the machine may operate. The amount of opening of the valve 15 is controlled by an adjusting screw 110 (Fig. 4) which determines the extreme left-hand position of the link 17.

The parts are shown in Fig. 4 just after the beginning of the downward travel of the work

head and the rods 12 and 14 associated with said head. The middle finger 45 has engaged the arm 51 and has shifted the valve 31 at the top of the stroke, with the spring 36 (Fig. 5) completing the valve movement to the operative position shown in Fig. 4. At the lower end of the stroke, the upper finger 44 will engage the finger 50 and the valve 30 will be shifted to its reverse operative position, with the parts as shown in Fig. 5.

10 If it is now desired to have the reciprocating parts travel upward or over-run to a more elevated position for inspection or reloading or any other purpose, the handle 92 (Fig. 1) is pulled forward until the spring-pressed ball 106 enters the recess 107.

It is important that the axial shift of the sleeve 52 from the position shown in Fig. 1 to the position shown in Fig. 2 take place only when the reciprocating parts are substantially at their lower limit of travel.

20 For this reason, pulling forward of the handle 92 merely tensions the spring 96 and slides the bar 91 forward relative to the bar 90, but the bar 90 cannot move until the collar 104 on the rod 14 approaches its lower limit of travel and engages and releases the latch lever 102.

25 The spring 96 then acts on the lever 80 (Fig. 1) to swing the same anti-clockwise, which in turn swings the arms 65 of the yoke lever 60 to shift the sleeve 52 to the left to the position shown in Fig. 2, in which position the parts are retained by engagement of the latch 72 with the segmental portion 71 of the plate 70.

30 The valve parts are now in the position shown in Fig. 2, with the arms 50 and 51 aligned with the inner upper finger 43 and with the lower finger 46.

35 The range of travel of the reciprocating parts will now be increased by the vertical distance between the middle finger 45 and the lower finger 46 (Fig. 4), thus providing an over-run in the upward direction which may be of any desired extent, depending on the vertical adjustment of the member 42 and finger 46 (Fig. 4) on the rod 12.

40 The work head will now continue to be reciprocated with upward over-run so long as the handle 92 is left in the described intermediate position.

45 In order to stop the machine, the handle 92 is pulled fully forward, with the ball 106 entering the recess 108. Such complete forward movement causes the lever 80 to engage the pin 85 (Fig. 1) on the plate 82 and to swing the plate counter-clockwise, which in turn swings the lever 18 to the right in Fig. 4 and moves the link 17 to close the throttle valve 15, thus stopping the reciprocating parts at their upper limit of travel or in any other desired position.

50 To start the machine up again, the lever 92 is shoved rearward, returning the lever 80 to the position shown in Fig. 1 and thus moving the plate 82 and lever 18 to open the throttle valve 15. It is essential, however, that the valve sleeve 52 be held in its outer or over-run position until the middle finger 45 is below the arm 51. Otherwise the arm will be broken.

55 It is for this reason that the latch plate flange 71 (Fig. 8) is made segmental. The segmental flange will not be moved out of alignment with the latch 72 to release the sleeve 50 until the plate 70 has been turned angularly with the valve 30 by the upper finger 43 at the lower reversal of travel.

60 In the meantime, the spring 86 (Fig. 1) has been compressed and held loaded by the lever 75 80. As soon as the plate 70 is released from the

latch 72, the spring 86 acts through the yoke lever 60 to return the sleeve 52 to the running position shown in Fig. 1.

The machine will now operate with normal or short travel so long as the lever 92 remains in its rearmost position and the latch lever 102 will prevent movement of the parts from this position except at the lower limit of travel, when the collar 104 releases the latch lever.

I have thus provided convenient and effective means permitting upward over-run of the reciprocated parts whenever desired and to a definitely predetermined extent. I have also provided for stopping the machine at any desired point during the over-run operation and I have provided for re-starting the machine and for automatically restoring the short or normal travel during the first reciprocating cycle. I have also provided safeguards which prevent shifting of the sleeve 52 axially on the shaft 31 except when the reciprocating parts are at or near their lower limit of travel.

Having thus described my invention and the advantages thereof, I do not wish to be limited to the details herein disclosed, otherwise than as set forth in the claims, but what I claim is:

1. A valve control mechanism for a reciprocated device comprising a reversing valve, regular means to operate said valve to provide a normal locus of reciprocation, additional means to operate said valve to provide over-run, a control device to shift control from said over-run to said normal-locus, and means effective to store a shift-indication by said control device until said reciprocated device has reached that end of the locus of normal reciprocation which is not altered by over-run and to thereupon release said shift-indication.

2. A valve control mechanism for a reciprocated device comprising a reversing valve, mechanical means to shift said valve to reverse the direction of travel of said reciprocated device

5 at each end of the normal locus of reciprocation, means to move a part associated with said reversing valve out of alignment with said mechanical means, and additional mechanical means to engage said valve part and to shift said valve to reverse the direction of travel of said reciprocated device at each end of a longer locus of reciprocation.

3. A valve control mechanism for a reciprocated device comprising a reversing valve, a sleeve on said valve, arms on said sleeve, a pair of fingers engaging said arms to reverse said valve, means to shift said sleeve axially, and a second pair of fingers engaging said arms to reverse said valve in the shifted axial position of said sleeve.

4. A valve control mechanism for a reciprocated device comprising a reversing valve, regular means to operate said valve to provide a normal locus of reciprocation, additional means to operate said valve to provide over-run, a manual device to render said regular means and said additional means alternately and selectively operative, a throttle valve, and connections from said 20 manual device to said throttle valve including a lever mounted on a floating pivot and linkage between said pivot and said throttle valve through which further movement of said device in the same direction is effective to shift said floating pivot and to thereby close said throttle valve and stop reciprocation.

FORREST R. WHITCOMB.
